(57) **CLAIM**

The ornamental design for a post-mix beverage dispensing tap valve, as shown and described.

DESCRIPTION

FIG. 1 is a side perspective view of the post-mix beverage dispensing tap valve showing my new design;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate portions of the post-mix beverage dispensing tap valve that form no part of the claimed design.

1 Claim, 4 Drawing Sheets
